UNITED STATES PATENT OFFICE.

FRANCIS B. BADT AND GEORGE M. WILLIS, OF CHICAGO, ILLINOIS.

BOND.

No. 826,136.

Specification of Letters Patent.

Patented July 17, 1906.

Application filed March 10, 1902. Serial No. 97,499.

To all whom it may concern:

Be it known that we, FRANCIS B. BADT and GEORGE M. WILLIS, citizens of the United States, residing at Chicago, in the county of Cook and State of Illinois, have invented a certain new and useful Improvement in Bonds, (Case No. 2,) of which the following is a full, clear, concise, and exact description, reference being had to the accompanying drawings, forming a part of this specification.

In electric railway practice contiguous rails are frequently bonded together, especially when the rails form a return-circuit, and it is necessary to make good electrical connections between adjacent rails. Although our invention is not thus limited, still it is particularly useful in applying the terminals of rail-connecting bonds to the ends of the rails which are to be electrically united.

The objects of our invention are principally to secure an efficient and durable connection, both electrically and mechanically, between bond-terminals and the rails to which they are applied.

A hole is usually formed in the web of the rail near either end. The bond consists of a heavy wire or cable-conductor terminating at either end in a soft copper lug or terminal and each adapted for insertion into the hole in one of the two rails which are to be connected.

Our invention provides a novel method of fastening the terminal within the hole in the rail. The terminal is of such size that it may be inserted easily within the hole in the rail.

A recess is formed in each end of the terminal, these recesses extending inwardly, so that a comparatively thin web is formed between the bottoms of the two recesses. This web of soft copper is of less thickness than the part of the rail into which the terminal is inserted. By the application of equal and opposite compressing forces upon the surfaces at the bottoms of the recesses on either side of the terminal web a lateral flow of the metal of the terminal web is produced.

This metal first flows from the axis of the terminal in generally radial directions until the hole in the rail is completely filled by metal under great compressive stress and then outwardly in directions more or less nearly parallel with the axis of the terminal. The compressing forces are applied by a suitable compressing-tool, which may be provided with hardened plugs to extend to the bottoms of the recesses of the terminal, or, as we prefer, the terminals may be permanently provided with hardened

plugs fitting within the recesses. In this preferred arrangement the compressing forces are transmitted by the hardened plugs directly to the thin web of copper between them. As distinguished from methods of the prior art, the compressing forces are directly applied to the soft flowing material of the terminal in an axial direction upon limited surfaces lying between the planes of the surfaces of the object through which the terminal has been inserted.

The result of our method is that we not only have sufficient metal of the terminal web to form a good electrical conductor, but the web itself acts as a compression member to maintain an exceedingly tight fit between the terminal and its hole after the compressing-tool has been removed.

We will explain our invention more fully by reference to the accompanying drawings, in which—

Figure 1 illustrates generally two rails bonded by means of our invention. Fig. 2 is a sectional view on line 2 2 of Fig. 1. Fig. 3 illustrates a compressor for completing the bond. Fig. 4 is a view similar to Fig. 2, the compressor having been employed, however, to complete the electrical connection between the bond and the adjacent rails. Fig. 5 is a sectional plan view of a modified form of rail-bond that may be employed. Fig. 6 illustrates a compressor adapted to unite this form of rail-bond with the rails. Fig. 7 illustrates in detail the plugging devices with which the device of Fig. 6 may be equipped. Fig. 8 illustrates the bond of Fig. 5 after it has been subjected to the action of the compressor to complete its connection with the rails; and Fig. 9 is an end view of one of the terminals of the bond shown in Fig. 8.

Like parts are indicated by similar characters of reference throughout the different figures.

The structural parts that are to be electrically united are in the drawings shown to be the rails *a a*, that may be used in an electric-railway system. Suitable portions of the structural parts *a a*—as, for example, the webs *b b*—may be provided with holes *c c*, that are preferably caused to extend entirely through the same. These holes may be of any suitable shape. We have illustrated holes each of which is of uniform diameter; but we do not wish to be limited to holes of this character.

The bond may have a link or yoke *d*, pref-

erably in the form of a bond wire or cable, such as illustrated most clearly in Fig. 1, which unites the terminals or terminal lugs *e e*, the holes *c c* in the adjacent rails being spaced apart a distance equal to the distance separating the said lugs and preferably being slightly larger than the terminals, so that the terminals may be readily inserted therein. The terminals *e e* are preferably provided each with two recesses *f f* in alinement, between which intervenes a web *g*, preferably of the same material as the balance of the lug.

The thickness of the web of the terminal is made less than the thickness of the web of the rail within which the terminal is to be fastened. The recesses *f f* preferably permanently contain plugs *h h*, about which the copper of the terminal lug is cast. These plugs *h h* may be formed of phosphor-bronze or other hard material having, preferably, a high coefficient of electrical conductivity. The preferred construction is illustrated in Figs. 2 and 4. In Figs. 6 to 8, inclusive, we have illustrated plugs *i i*, that are adapted for reception within the central recesses *f f* only when the joint is being completed. A third way of completing the joints might consist in employing plugs similar to plugs *h h* of Figs. 1 and 4, but having them not integrally formed with the lugs, in which case the plugs *h h* would then merely serve the function of a tool, which having effected the lateral distension of the lugs may thereafter be removed. We prefer, however, the construction wherein plugs *h h* are integrally formed with the terminal lugs of the bonds, for reasons which have been stated.

As will be apparent from an inspection of the drawings, the surfaces of the web of the terminal having less distance between them than the surfaces of the web of the rail lie both within the planes of the surfaces of the web of the rail. It is to these surfaces of the web of the terminal that the compressing forces are directly applied, and the surface to which the compressing forces are applied is obviously of less diameter and area than the terminal.

In Figs. 2 and 5 we have shown rail-bonds which span the gap between adjacent rails, the bases of the terminal lugs being united by the link or yoke *d*, while the free ends of the terminal lugs are unheaded. In these views the thickness of the webs *g* will be observed. In Figs. 4 and 8 the thickness of these webs has been reduced, the metal of the web having been spread laterally to increase the diameter of the lugs *e e* where they pass through the holes *c c*. The recess at the base of the terminal lug is slightly flared for the purpose of enabling the plugging-tool that enters the same to be readily withdrawn. The recess at the opposite end of the terminal lug is preferably more widely flared, so that the metal at the extreme end may be spread

laterally to form a head *k*, the metal portion *a* being thus confined between the head *k* and the base of the terminal lug.

One of the principal distinctions between the method of applying rail-bonds as heretofore practiced and that of our present invention may be described as follows: It has been the practice in methods heretofore employed to insert a terminal within an opening in the web of a rail. This terminal has passed entirely through the web of the rail extending some distance to either side of the surfaces of the rail-web. A pressure was exerted on the opposite ends of the projecting terminal, thereby causing a compression and upsetting of the terminal until it filled the opening in the rail, the projecting ends being headed or riveted over to prevent the terminal from falling from the rail. In practicing this method there has been caused some flow of metal transversely with respect to the axis of the terminal, but the entire quantity of the material of the terminal within the planes of the surfaces of the rail-web has been placed under a compressive strain caused by forces exerted and transmitted from points outside of the surfaces of the rail-web and transmitted only by the soft material of the terminal itself. Upon the removal of the forces which have caused this compression the terminal expands, due to the resilience of the copper of which it is preferably formed, this expansion being in the direction in which the compressive forces have been applied. There has been a consequent decrease in the diameter of the terminal upon the removal of the compressing forces. This has caused a considerable loosening of the terminal within the hole in the rail. By our method the forces which are applied to the web of the terminal are applied at points lying within the planes of the surfaces of the rail-web. These forces cause a flow of the metal of the terminal laterally in generally radial directions from the axis of the terminal until the opening within the rail is filled. Thereafter the flow of the metal, due to the continued force applied by the plugs *h h*, causes a flow of the metal of the terminal outwardly on either side between the plug and the hole in the rail toward the surface of the rail-web. Thus the metal of the terminal between the web of the terminal and the surface of the rail-web is put under a compressive strain, the force causing this compressive strain being applied from the inside of the terminal—that is, from the material forming the web of the terminal rather than from the outside of the terminal, as in methods of the prior art. This outward flow of the metal lying between the plug and the hole in the rail-web is opposed and resisted by the friction between the plug and the flowing metal. Upon the removal of the pressure applied to the plugs *h h* the resilience of this metal between the web of the terminal and

the surfaces of the rail causes a tendency of the metal to crowd back from the surfaces of the rail-web toward the web of the terminal. Thus after the removal of the pressure upon the terminal plugs the resilience of the metal of the terminal causes a continuing compressive stress to be exerted upon the terminal web, this stress serving to maintain the web of the terminal of large diameter, whereby a much greater force is continuously exerted between the terminal and the hole in the rail-web than has been secured by methods heretofore employed. When the plugs are mechanically integrally formed with the bond-terminals, the friction between the sides of the plug and the metal terminal also serves to maintain a pressure upon the terminal web in the direction in which the upsetting forces were applied, thus further serving to maintain the web in compression after the removal of the compressing-tool.

It will be seen that our invention contemplates the application of the compressing forces directly to the material of the terminal at points which lie between the planes of the surfaces of the rail-web. Even after the removal of the compressing-tool the compressing stresses upon the terminal web are maintained in the same direction as that in which they were applied to upset the terminal.

We have not deemed a detailed description

of the compressing device to be essential, as such devices are well known to those skilled in the art. Obviously other means may also be employed to effect the compression within the terminal lugs. While we have shown terminal lugs each having two recesses, we do not wish to be limited in the use of our invention to such a structural characteristic.

Having thus described our invention, we claim as new and desire to secure by Letters Patent—

The herein-described method of fastening a terminal within a hole which consists in subjecting the plastic material of the terminal to pressures initially applied below the planes of the surfaces at the ends of said hole, thereby producing a flow of said plastic material first in a longitudinal direction, then outwardly from the axis of the terminal and substantially at right angles to said axis and finally in a direction parallel with the axis of said terminal but from the interior toward the outer ends of said terminal.

In witness whereof we hereunto subscribe our names this 7th day of March, A. D. 1902.
